Primary Examiner — Eric Goodman*Assistant Examiner* — Luqman McNeil(74) *Attorney, Agent, or Firm* — Robert C. Montgomery; Montgomery Patent & Design, L.P.**CLAIM**

The ornamental design for a cleaning attachment for a leaf blower nozzle, as shown and described.

DESCRIPTION

FIG. 1 is a perspective front view of a cleaning attachment for a leaf blower nozzle, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
